UNITED STATES PATENT OFFICE.

JAMES ALFRED SMITH, OF NEW BRITAIN, CONNECTICUT, ASSIGNOR TO THE LANDERS, FRARY & CLARK, OF SAME PLACE.

DESIGN FOR A CASE FOR SPRING-BALANCES.

SPECIFICATION forming part of Design No. 27,545, dated August 17, 1897.

Application filed June 11, 1897. Serial No. 640,388. Term of patent 14 years.

To all whom it may concern:

Be it known that I, JAMES ALFRED SMITH, a citizen of the United States, residing at New Britain, in the county of Hartford and State of Connecticut, have invented and produced a new and original Design for a Case for Spring-Balances, of which the following is a specification, reference being had to the accompanying drawings, in which—

- 10 Figure 1 is a front elevation of a spring-balance case, showing my design. Fig. 2 is a side elevation thereof.

As shown in the drawings, the leading or material feature of my design consists of a short cylindrical portion with a large diameter in proportion to its length, thereby forming what I may term a "disk-like" upper case, a smaller neck portion depending from the lower edge of said disk-like case, and a long cylindrical portion or lower case with a comparatively short diameter, having its ends extended in both directions from the lower end of said neck portion, the said long and short cylindrical portions being relatively arranged with their axes extending at right angles to each other.

A designates the short cylindrical portion

of the case, which I call the "disk-like" upper case. The corners 3 at each end or broad side are beveled off, as best shown in Fig. 2. The 30 neck B depends from the lower edge of the part A and is of an oval form in plan view. The long cylinder or lower case C is mainly a plain cylinder arranged at the lower end of the neck B and with its ends extending laterally in both directions from said neck. On the front of the cylinder C there is a longitudinal ledge or band 4, having slots 5, the parts being relatively arranged as shown. The parts represented in broken lines, although 40 intended to be used with the case, are not a part thereof, and therefore are not of my design.

The several portions may, it is manifest, be engraved, chased, or otherwise ornamented, 45 as desired.

What I claim as new, and desire to secure by Letters Patent, is—

The design for a spring-balance case substantially as herein shown and described.

JAMES ALFRED SMITH.
